UNITED STATES PATENT OFFICE.

HERMAN MORITZ, JOSEPH J. KOELSCH, AND FRANK KOEHN, OF DURHAM, KANSAS.

SINGLE-TRIGGER MECHANISM.

1,145,502.

Specification of Letters Patent.

Patented July 6, 1915.

Application filed November 19, 1912. Serial No. 732,351.

To all whom it may concern:

Be it known that we, HERMAN MORITZ, JOSEPH J. KOELSCH, and FRANK KOEHN, citizens of the United States, residing at 5 Durham, in the county of Marion, State of Kansas, have invented certain new and useful Improvements in Single-Trigger Mechanisms; and we do hereby declare the following to be a full, clear, and exact description 10 of the invention, such as will enable others skilled in the art to which it appertains to make and use the same.

The object of the invention resides in providing means whereby a firearm which includes independent firing mechanism may be operated through the medium of a single trigger to fire said mechanism singly.

A further object of the invention resides in the provision of a single trigger mechanism for firearms which may be readily associated with any standard double barrel firearm employing an independent firing mechanism for each barrel.

With the above and other objects in view 25 25 the invention consists in the details of construction and in the arrangement and combination of parts to be hereinafter more fully described and particularly pointed out in the appended claim.

30 In describing the invention in detail reference will be had to the accompanying drawings wherein like characters of reference denote corresponding parts in the several views, and in which—

35 Figure 1 is a side view of the lock mechanism with the trigger plate partly in section; Fig. 2 a horizontal section of a fragment of what is shown in Fig. 1 with the parts of the single trigger mechanism in the 40 position they would occupy when both firing mechanisms of the gun are in cocked position. Fig. 3 a view similar to Fig. 2 with the parts of the single trigger mechanism in the position they would occupy after the left 45 hand firing mechanism of the gun has been fired. Fig. 4 a plan view of the trigger plate, trigger and the parts carried by said trigger plate and trigger. Fig. 5 a detail perspective view of the tripping lever of the single trigger mechanism, and Fig. 6 a detail perspective view of the trigger detached.

Referring to the drawings, A indicates the breech of the gun and B the trigger plate which is attached to the breech in the usual and well known manner. Mounted upon the breech A are left and right hand firing

mechanisms C and D respectively. These firing mechanisms C and D are of the usual and well known construction and each includes a hammer 10 and sear 11, the sears 11 of the right and left hand firing mechanisms being L-shaped, as is customary and disposed in opposition to each other, the long arm of each sear 11 being disposed longitudinally of the gun and the short arm transversely. Each of the firing mechanisms C and D further includes a tumbler 12 adapted to be engaged by a respective sear 11 to hold the adjacent firing hammer in cocked position, it being understood that said firing hammer is suitably connected with the tumbler 12 so as to be moved under the influence of the cocking of the hammer to bring a desired notch thereof into position to be engaged by the adjacent sear 11.

Pivotedly mounted in the usual opening in the trigger plate B is a trigger 13 which is held in normal position by means of a leaf spring 14 mounted upon the inner face of the trigger plate B. Pivotedly mounted upon the top of the trigger 13 is a tripping lever E which includes a forward section 15 and a tail piece 16, the latter being disposed beneath the short arms of the sears 11 and movable in a horizontal plane transversely 50 of the gun so as to position said tail piece under the short arm of the sear of either the right hand or left hand firing mechanism. The free end of the forward section 15 of the tripping lever E is provided with a laterally bent portion 17 directed toward the left hand firing mechanism C and positioned to pass in front of the tumbler 12 when the left hand hammer 10 is in non-retracted position. When the left hand hammer C is retracted the laterally bent portion 17 will be engaged by the tumbler 12 associated with the firing mechanism C and moved inwardly and transversely of the gun so as to swing the tail piece 16 beneath the short arm of the sear 11 which locks the hammer of the firing mechanism C in cocked position. When the tail piece is in this position the actuation of the trigger 13 will disengage the sear 11 of the left hand firing mechanism from the notched plate 12 and fire the left hand hammer as will be obvious. The tripping lever E is normally held in position to dispose the tail piece 16 beneath the short arm of the sear 11 associated with the right hand firing mechanism D by means of a leaf spring 18 mounted upon

the inner face of the trigger plate B and bearing against the side of the tail piece 16 adjacent the firing mechanism C. Through the instrumentality of this spring 18 it will be apparent that as soon as the left hand hammer 10 is fired the laterally bent free end 17 of the extension 15 of the tripping lever will be forced across the front of the tumbler 12 of the firing mechanism C and 10 the tail piece 16 simultaneously moved beneath the short arm of the sear 11 associated with the firing mechanism D so that the 15 next actuation of the trigger 13 will cause the tail piece to engage the sear 11 of the firing mechanism D and release the right hand firing hammer 10.

It will of course be apparent that if only the right hand firing hammer is cocked the tail piece 16 will remain beneath the short 20 arm of the sear 11 associated with the firing mechanism D when actuation of the trigger 13 will release the right hand hammer. However, as soon as the left hand hammer 10 is cocked the tail piece 16 will be moved 25 against the influence of the spring 18 to a position beneath the short arm of the sear 11 of the firing mechanism C in the manner heretofore described, when the actuation of the trigger 13 will fire the left hand hammer 30 and the next actuation of the trigger will fire the right hand hammer if same be cocked.

While the single trigger mechanism has been shown constructed so as to operate the 35 left hand hammer first it will be apparent

that said mechanism may be readily reversed so as to fire the right hand hammer first if desired.

What we claim is:—

In a firearm, the combination of a guard 40 plate, a pair of firing mechanisms, a sear associated with each mechanism for holding same in cocked position, a trigger pivotally mounted for movement in an opening in the guard plate, a tripping lever pivoted on said 45 trigger and including a forward extension and a tail piece, a leaf spring having one end secured to the trigger plate with its widest face in engagement with said plate, the other end of said spring engaging said 50 tail piece and constantly tending to move same in operative relation to the sear of one of said firing mechanisms, said leaf spring being twisted to dispose the widest face thereof against the tail piece, and a 55 laterally bent end on the forward extension adapted to be engaged by an element of the other firing mechanism whereby the cocking of the last named firing mechanism will move the tail piece of the lever into operative 60 relation with respect to the sear of said last named firing mechanism.

In testimony whereof, we affix our signatures, in presence of two witnesses.

HERMAN MORITZ.
JOSEPH J. KOELSCH.
FRANK KOEHN.
